UNITED STATES PATENT OFFICE

CHARLES BLIEBERGER, OF NEW YORK, N. Y.

LOUD SPEAKER

Application filed January 18, 1930. Serial No. 421,644.

The present invention relates broadly to acoustics and more especially to a sound producing apparatus comprising a loud speaker for radios, address systems, phonographs, etc.

It is particularly desirable in loud speaking apparatus to provide constructions adaptable for responding, under power impulses, to a large range of sound waves, and also to be capable of response to complex sound waves such as voice, etc., without distortion.

One of the difficulties in producing air waves mechanically is to provide a mechanism which does not possess a definite normal rate of vibration and thereby tend to over-amplify air waves which correspond to the zone of normal vibrations of the mechanical device itself.

The present invention overcomes the difficulties of the known art by providing a mechanical structure adaptable to be electrically or otherwise power operated and whereby a fidelity of tone reproduction is obtained because of the uniform response to the air wave produced throughout a very wide range of tones. The desirable effects of the present invention appear to be brought about by providing and suitably mounting a diaphragm member capable of response to a wide range of tones and wherein the diaphragm is equally responsive to the tones in a wide range without being over responsive to any particular zone of waves. The diaphragm in the present case is therefore constructed in such manner as to obviate its individual characteristic as a whole to any particular tone or harmonic of that tone. One form of the present invention comprises the production of a diaphragm of substantially circular shape with a portion of the diaphragm being relatively thick and tapering from the thick portion to an edge of uniform thickness. This thick portion is offset an incommensurate distance from the center

of the diaphragm so that it obviates undue harmonic vibrations, and since the thickness of the diaphragm tapers in all directions from this high point to the edge of uniform thickness, sections cut through the diaphragm in various directions respond to waves of different frequencies and vibrate wedge shaped portions of the diaphragm having their thick base adjacent the thick point of the diaphragm and their points of a uniform thickness, due to the uniformity of thickness of the edge of the diaphragm. By this construction, it will be observed that portions of the diaphragm representing the longest distance from the thick spot to the edge will respond to one group of air vibrations and that the portion of the diaphragm determined by the shortest distance between the thick spot and the edge will respond at another zone of vibrations and that other parts of the diaphragm between these two maximum dimensions will respond to all intermediate tones. This result is brought about by the combination of the offset center and the varying thickness of the diaphragm. It is further brought about by dampening of the operating mechanism for the diaphragm. For example, the power communicating rod is preferably covered at suitable intervals with dampening material such as rubber tubing, which prevents any extraneous vibration being established in the operating rod, and the point of connection between the operating rod and the diaphragm itself is preferably a yielding connection such as a leather pad or some other resilient substance. The diaphragm in accordance with the present invention may be made of various materials but experimentation has shown that diaphragms made of wood are particularly effective, and some of the best results have been obtained by making the diaphragms of hard maple.

While the present invention is not limited to definite sized parts, experiments have

shown that a diaphragm in accordance with the following dimensions produce very satisfactory results. A board of hard maple $\frac{5}{16}$ ths of an inch in thickness cut away at the center 5 to provide a diaphragm 15 inches in diameter and with the edges of the diaphragm $\frac{3}{2}$ nd of an inch thick. The thick point in the diaphragm has a thickness of $\frac{3}{2}$ nds of an inch and is located on a center line of the dia- 10 phragm $4\frac{1}{4}$ inches from one side and $10\frac{3}{4}$ inches from the other side. These proportions are such that the results are very satisfactory. After the diaphragm has been cut 15 in accordance with the dimensions specified and carefully smoothed and polished, it is then preferably treated by being shellacked or varnished on both sides to obviate weather effects and also to fill the wood pores.

Diaphragms have been made of many other 20 materials other than wood and also in various different sizes, so that it is to be understood that the above disclosure is illustrative and not in the limiting sense.

The present invention may be embodied in 25 structures other than those herewith specifically disclosed and therefore it is to be understood that the disclosure is the preferred form in accordance with the patent laws and is not to be considered in the limiting sense.

Referring now to the drawings, Fig. 1 illustrates a diaphragm plate in accordance with the present invention.

Fig. 2 is a sectional view on line 2—2 of Fig. 1.

Fig. 3 illustrates the diaphragm mounted in a frame.

Fig. 4 is a vertical section through the construction shown in Fig. 3 and illustrating the operating mechanism.

Fig. 5 is a detail of the upper portion of Fig. 3.

Fig. 6 is a plan view of a diaphragm in accordance with the present invention.

Fig. 7 is a view on line 7—7 of Fig. 6.

Fig. 8 is a cross-section through Fig. 6 on line 8—8.

Fig. 9 is a cross section on line 9—9 of Fig. 6.

Referring now to the drawings. The dia- 50 phragm 1 is preferably constructed by cutting away one side of a wooden slab or board in such manner as to provide a thin vibratory diaphragm having a thick portion 4 from which the diaphragm tapers to an edge 5 of substantially uniform thickness. Preferably, 55 though not necessarily, the opposite side 6 of the diaphragm is a plain surface. The thick portion of both the diaphragm and the edges are exaggerated in the drawings in order to be able to illustrate these features.

As will be observed from Figs. 6, 7, 8, and 9, the thick portion 4 of the diaphragm is offset from the center of the diaphragm, and as measured along the diameter D which 60 passes through the center of the thick por-

tion 4 and the center of the diaphragm, this thick portion 4 is offset an incommensurate distance from the center of the diaphragm. This thick spot divides the total surface of the diaphragm in such manner as to prevent 70 the tendency to produce harmonic vibrations other than those desired and also divides the diaphragm in such manner as to provide a large number of incommensurate sectorial lines passing through the thick spot 4. This 75 renders the diaphragm particularly sympathetic to all wave lengths between those which are in harmony with the shortest portion of the diaphragm between the thick portion 4 and the edge 5, and those which are 80 in sympathy with the longest distance between the thick spot 4 and the edge 5 of the diaphragm. This sympathetic relationship is local to various parts of the diaphragm depending upon the particular wave length 85 which is being reproduced.

While the diaphragm is preferably made of wood, such as hard maple, which has been suitably varnished, the diaphragm may be also made of other materials such as pressed 90 paper, fiber board, metal, etc.

A preferred mounting for the diaphragm is to mount the frame portion 7 of the dia- phragm in a front board which preferably is made of two supporting members 8 and 9, 95 which are cut away at 10 and 11 to provide unobstructed openings of the size of the dia- phragm 1. Each of the supporting mem- bers 8 and 9 are recessed to receive substan- tially one half of the thickness of the frame 100 7 of the diaphragm and the diaphragm is tightly clamped between the supporting members 8 and 9, so that these members comprise front boards which rigidly support the dia- phragm 1 whereby the air vibrations are 105 established by the diaphragm itself. Prefer- ably, baffles 12, 14, 15 and 16 are secured to the front board and are open at the back with the exception of a unit support 17 which ex- tends between the baffles 12 and 14. These 110 baffles may comprise a wooden framework, preferably dove-tailed at the corners to form an open backwardly extending frame which screens the front of the diaphragm 1 from the back thereof in such manner that the air waves from the front of the diaphragm are not distorted by interference to the air waves from the back thereof.

Where the present invention is utilized as a telephonic loud speaker with a radio or a 115 loud speaker address system or the like, it preferably is operated by an electromagnetic unit such as is common in the art and which is carried upon the unit support 17. The connection between the unit 18 and the dia- phragm 1 preferably comprises a small 120 rod 19 which bears against a resilient pad 20 of leather or the like. Preferably, the contact between the driving rod 19 and the dia- phragm 1 is by lateral pressure of the end 130

of the rod 19 against the resilient pad 20. However, there may be occasions where it is desirable to permanently attach and anchor the rod 19 to the diaphragm. The application of power through the rod 19 is preferably directly over the thick spot 4 of the diaphragm so that this spot becomes the initial point of vibration of the diaphragm. In order to obviate any extraneous vibration being set up in the rod 19, the rod is damped by means of dampening members 21 which may comprise short separate sections of rubber tubing of sufficiently small diameter to be expanded slightly when the rod 19 is telescoped through these sections.

10 The device in accordance with the present invention as herein disclosed faithfully reproduces complex sounds through an extremely large range, and does not tend to 20 distort reproduced sound by over-amplification of any particular band of sound waves, and neither does it distort the sound waves because of extraneous waves introduced through the vibration of the connecting 25 parts.

While the diaphragm is disclosed as being circular in form, it is to be understood that the form herein shown is merely illustrative and that other shapes may be used with equal 30 facility.

Having described my invention, I claim:—

1. An acoustical diaphragm comprising a resonating member having a substantially circular edge of substantially uniform thickness, a thick zone tapering in all directions toward said edge, said thick zone being located on a diameter of said diaphragm and offset from the center of said diaphragm so that the distance from said thick zone measured along said diameter to one edge is incommensurate relative to the distance from said zone along said diameter to the other edge.

2. In an acoustical device, a diaphragm comprising a resonating member having a substantially circular edge of substantially uniform thickness, a thick zone tapering in all directions toward said edge, said thick zone being located on a diameter of said diaphragm and offset from the center of said diaphragm so that the distance from said thick zone measured along said diameter to one edge is incommensurate relative to the distance from said zone along said diameter to the other edge, and driving means operative to deliver power to said thick zone to vibrate said diaphragm.

3. An acoustic diaphragm comprising a relatively thick slab provided with a circular depression, the edges of said diaphragm being substantially uniform in thickness and with a thickened zone offset from the center of said depression and sloping in all directions to the edge thereof.

4. In an acoustic diaphragm comprising

a relatively thick slab provided with a circular depression, the edges of said diaphragm being substantially uniform in thickness and with a thickened zone offset from the center of said depression and sloping in all 70 directions to the edge thereof, and driving means operative on said thickened zone.

5. An acoustic diaphragm comprising a slab having a thick portion and a depression therein forming a thin vibratory member 75 supported by the thick portion of said slab.

6. In an acoustic device, a diaphragm comprising a slab having a thick portion and a depression therein forming a thin vibratory member supported by the thick portion of 80 said slab, and driving means to vibrate said thin vibratory member.

7. An acoustical diaphragm comprising a circular member with a substantially uniformly thick edge, and with a thick zone 85 tapering toward said edge; the proportions of said diaphragm being diameter fifteen units, and the thick zone being offset three units from the center of said diaphragm.

8. An acoustical diaphragm comprising a circular member with a substantially uniformly thick edge, and with a thick zone tapering toward said edge; the proportions of said diaphragm being diameter fifteen units, the thick zone being offset three units 90 from the center of said diaphragm, the thickness of the thick zone being substantially three times the thickness of said edge.

9. In an acoustical device, a diaphragm comprising a slab provided with a circular depression, an anchoring frame having openings substantially the size of said depressed portion and adapted to clamp said slab with the depressed portion thereof exposed, means to support said anchoring frame, and driving 100 means for vibrating said depressed portion 105 of said slab.

10. In an acoustical device, a diaphragm comprising a slab provided with a circular depression, an anchoring frame covering portions of both sides of said slab and having openings substantially the size of said depressed portion and adapted to clamp said slab with the depressed portion thereof exposed, means comprising a baffle member to 110 support said anchoring frame, and driving means for vibrating said depressed portion 115 of said slab.

11. An acoustical device comprising a slab having a thick portion and a thin portion with a thin portion comprising a resonating diaphragm, anchoring means for supporting the thick portions of said slab against vibration, means to support said anchoring means, and driving means to vibrate said thin portion.

12. An acoustical device comprising a slab having a thick portion and a thin portion with the thin portion comprising a resonating diaphragm with the mass of said diaphragm 120 125

non-uniformly disposed relative to the geometric center of the diaphragm, anchoring means for supporting the thick portions of said slab against vibration, means to support 5 said anchoring means, and driving means to vibrate said thin portion.

13. In an acoustical device, a diaphragm, power means for operating said diaphragm, said power means comprising an operating 10 pin, and vibration dampening means to prevent transverse vibration to said pin.
